INFLATABLE LOUNGE

Louis R. Des Pres, East Haven, Conn., assignor to Divers International, Inc., New Haven, Conn.

Filed Oct. 24, 1969, Ser. No. 19,709

Term of patent 14 years

Int. Cl. D6—01

U.S. Cl. D15—11

FIG. 1 is a top plan view of the inflatable lounge embodying my new design;

FIG. 2 is a front elevational view of the inflatable lounge shown in FIG. 1;

FIG. 3 is a side elevational view of the inflatable lounge shown in FIG. 1, the opposite side elevational view being identical;

FIG. 4 is a back elevational view of the inflatable lounge shown in FIG. 1;

FIG. 5 is a bottom plan view of the inflatable lounge shown in FIG. 1.

I claim:

The ornamental design for an inflatable lounge, as shown and described.
